(57) CLAIM

The ornamental design for an elevated wooden spoon, as shown and described.

DESCRIPTION

FIG. 1 is a perspective view of the elevated wooden spoon showing my new design.

FIG. 2 is a top view thereof.

FIG. 3 is bottom view thereof.

FIG. 4 is front view thereof.

FIG. 5 is back view thereof.

FIG. 6 is a side view thereof; and,

FIG. 7 is another side view thereof.

The broken lines shown in the drawings are for illustrative purposes only and form no part of the claimed design.
